UNITED STATES PATENT OFFICE

ARTHUR PRIMROSE YOUNG, OF KENILWORTH, AND JOHN H. BUTCHER, OF RUGBY, ENGLAND, ASSIGNORS TO GENERAL ELECTRIC COMPANY, A CORPORATION OF NEW YORK

TELEPHONE DEVICE

Application filed August 18, 1925, Serial No. 51,032, and in Great Britain October 21, 1924.

This invention relates to sound-emitting and transmitting apparatus, and particularly to hornless loud-speaking telephones for use in the reception of wireless telephony, which instruments are also suitable for use as "pick-ups", i. e., to receive sound and convert it into electric oscillations.

More particularly it relates to hornless loud-speakers comprising an electromagnetic 10 vibrator unit which is adapted to influence a conically-shaped diaphragm substantially within which the vibrator unit is arranged.

In instruments of this class, according to the invention, an open-work cover-plate is 15 adapted to prevent damage to the more delicate parts of the instrument.

The diaphragm may be made of leatheroid or other suitable material and may be provided with an annular groove near its periphery in a manner that is known in order that it will move substantially as a whole when actuated by the vibrator unit, the apex of the diaphragm being adjustably connected to the vibratory member. The periphery of 25 the diaphragm may be gripped by means of clamping screws between a ring and the cover plate, which is preferably in the form of an open-work dome-shaped cage adapted to protect the diaphragm and to allow the 30 emission of sound. The apex or central portion of the cover-plate may be provided with a detachable member to facilitate the adjustment of the connection between the diaphragm and the vibratory member. The 35 concave side of the diaphragm is preferably closed by a back cover-plate secured both to the vibratory unit and to the periphery of the front cover-plate.

With this arrangement a pleasing looking bell-shape loud-speaker is produced, which 40 may be mounted with the main axis of the conical diaphragm in a vertical or horizontal plane, either hanging from the ceiling or a bracket, or supported by a suitable stand or legs adapted to rest on a table or other support.

The diaphragm is relatively large compared with the vibrator unit; for instance, the diameter of the base of the diaphragm 50 may be approximately three times that of the

vibrator unit. Preferably, the rear cover-plate is secured to the vibrator unit so as to provide means for reaching an adjusting device on the vibrator unit whereby the magnetic structure thereof may be moved towards or away from the cooperating vibratory member.

The novel features which we believe to be characteristic of our invention are set forth with particularity in the appended claims. 60 Our invention, itself, however, both as to its organization and method of operation will best be understood from the following description taken in connection with the accompanying drawing in which Fig. 1 is a 65 partial cross section and elevation of the device. Figs. 2 and 3 show the loud-speaker supported in horizontal and vertical positions respectively.

Referring to the drawing, 11 denotes an 70 electro-magnetic vibratory unit which may be of any suitable type. The vibratory member 12 thereof is connected by the rod 13 to the conically-shaped diaphragm 14, the connection including an adjusting device, such, for instance, as the screw 15 which engages with the bushing 16 and bears against the connecting rod 13. The inner end of bushing 16 is provided with a flange 17 between which and the nut 18 the diaphragm 14 is securely clamped. At the points of connection the diaphragm may be strengthened, as indicated at 19. Near the edge of the diaphragm there is provided an annular groove 21, which acts as a flexible support for the diaphragm, whereby the same will vibrate substantially as a whole when operating. 80 The edge 22 of the diaphragm is gripped between the supporting ring 23 and the edge 24, of the open-work cover-plate 25. The open-work cover-plate may be formed so that its center portion 26 is removable, an outwardly-turned flange 27 on the cover-plate 85 making a good connection with the cap 28. The 90

As illustrated in Fig. 1, the edge of the cover-plate 25 may be turned down as at 28 to provide a seating for the flange 29 of the annular back cover-plate 31. The cover-plate 31 cooperates with the cover-plate 25 to provide a housing for diaphragm 14. This back 100

cover-plate may be secured by the screws and nuts 32 which clamp the edge of the diaphragm between the ring 23 and the cover-plate 24. Its inner edge is here shown as being clamped to and supporting the vibrator units by means of the clamping devices 33 which hold vibratory member 12 in position with respect to the vibratory unit. This construction admits operation of the nut 34, by which the magnetic structure of the vibrator unit may be adjusted towards and away from its cooperating vibratory member.

In the construction shown in Fig. 2, a support comprising a ring portion 35 with which feet 36 are formed integrally is adapted to be secured to the edge of the unit, preferably by the clamping devices 32, the feet thus being connected directly with the open-work cover-plate 25.

20 In Fig. 3, the instrument is shown provided with a handle for use when it is being moved and a base portion 37 mounted on knobs or the like 38 and connected to the cover-plate at the front and the back thereof by stays 39.

25 It will be obvious, if it is desirable to suspend the instrument, that two or more chains may be connected thereto, for instance, to the clamping screws 32.

What we claim as new and desire to secure 30 by Letters Patent of the United States, is:

1. In combination, a substantially conical shaped diaphragm, a vibrator member, an adjustable connection between the vibrator member and diaphragm, and a cover member 35 secured at the edge of said diaphragm, said cover member having a removable portion adjacent said adjustable connection.

2. In combination, a substantially conical shaped housing, a substantially conical shaped diaphragm within said housing, means for clamping the diaphragm to the housing, means attached to said clamping means for supporting said housing, and vibratory means cooperating with said diaphragm.

3. In combination, a substantially conical shaped diaphragm, vibratory means associated with said diaphragm, a connection between said vibratory means and diaphragm, 50 a perforated substantially conical cover-plate for said diaphragm, said cover-plate having a downwardly extending flange, supporting means for said vibratory means, said supporting means having an upwardly extending flange portion adapted to cooperate with the downwardly extending flange on the cover-plate, and means for clamping said cover-plate to said diaphragm and supporting means.

60 4. The combination of a housing provided with an opening, a diaphragm within said housing, a vibratory member mounted in said opening and coupled to said diaphragm, means arranged to actuate said vibratory member, and means for adjusting the me-

chanical relation between said vibratory and actuating means.

In witness whereof, we have hereunto set our hands this 29th day of July, 1925.

ARTHUR PRIMROSE YOUNG. 70
JOHN H. BUTCHER.
